UNITED STATES PATENT OFFICE.

JOHN D. MOORE, OF MASSILLON, OHIO.

SPARK-PLUG PROTECTOR.

Application filed August 3, 1925. Serial No. 47,794.

This invention relates to spark plugs and has for its object to provide a spark plug protector of improved construction which will prevent fouling of the electrodes, without interfering with the proper firing of the cylinder.

The invention will be more clearly understood by reference to the accompanying drawings in which are shown illustrative 10 embodiments of the invention.

In the drawings:—

Fig. 1 is a central vertical section showing a spark plug provided with a preferred form of protecting device.

Fig. 2 is a similar view showing a modification, and

Fig. 3 shows a third modification of the invention.

In Fig. 1 is shown a spark plug which 20 possesses the general features common to nearly all spark plugs of standard type, including the insulator 10, central electrode 11, body portion 12, threaded as at 17, and the gland 13, suitable gaskets 14 and 15 being 25 employed at the joints. Side electrodes 16—16 extending from the body portion 12 cooperate with the central electrode 11 to produce the spark.

The invention consists in the provision 30 of an attachment designed to prevent oil from reaching the electrodes, and also designed to protect the insulator 10 from direct contact with the hot gases in the main cylinder. As shown in Fig. 1, the 35 attachment comprises a shell internally threaded at 17' and adapted to be secured onto the body 12 of the spark plug. The shell is also provided with a nipple 18 which is adapted to be screwed into an engine 40 cylinder. As shown, this shell is provided with additional side electrodes which are adapted to coat with a reduced portion 20 of the central electrode 11. An important feature of the invention is the provision 45 of a tapered or conical choke member 21, integral with the body of the shell and surrounded by the nipple 18 which prevents access of oil except through the single reduced orifice 22 at the center of the choke member. The chamber 23 formed by the choke member is an initial combustion chamber in which gas is exploded by the spark 50 of the upper side electrodes 16 and the central electrode 10.

A second chamber 24 in direct communica-

cation with the main combustion chamber is provided below the choke member 21, and a second spark gap is provided between the choke member and the reduced portion 20 of the central electrode. A third spark 60 gap is provided within the combustion chamber proper by button electrodes 19 and the central electrode. In this manner, instantaneous firing of the entire charge is assured.

It will also be noted that the upper electrodes and the insulator are completely protected from oil and from the direct heat of the main combustion chamber by means of the choke members 21 and that the choke member itself is partially protected by means 70 of the nipple 18. By reducing the size of the central electrode, the size of the orifice 22 in the choke member may be reduced, whereby greater protection is afforded the upper electrodes and the insulator. Another 75 advantage of the present construction is the reduced size of the combustion chamber 23 and the short passage connecting the same with the main combustion chamber, thus insuring simultaneous combustion in both 80 chambers. A further advantage of the reduced size of chamber 23 is the diminished amount of heat generated therein, whereby all danger of breaking or cracking the insulator is avoided.

The invention is, of course, subject to modifications. For example, in Fig. 2, I have shown a spark plug having but one side electrode, and a protecting device in which the lower electrodes are eliminated. 90 This does away with the necessity for the extension of the central electrode. This device may be used under certain circumstances, but the form shown in Fig. 1 is preferred.

In Fig. 3 is shown a still further modification. In this construction the protecting device is of three parts comprising a sleeve 30 secured to the body of the spark plug and having a threaded nipple 31 to which is secured a lower sleeve 32 having a nipple 33 designed to be screwed into the engine cylinder. A separate choke member 34 is held in place by the lower sleeve 32, suitable gaskets 35 being provided. The central orifice 36 of the choke member is of Venturi shape.

Other modifications within the scope of the invention will occur to one skilled in the art.

Having thus described my invention, what I claim as new and desire to secure by Letters Patent is:—

The combination with a complete spark plug having a central electrode, and having a threaded nipple, and side electrodes extending inwardly from said threaded nipple an cooperating with said central electrode, of a removable protecting device for said electrodes adapted to be secured to said nipple and having a tapering choke member extending inwardly and downwardly from the body of said protecting device and forming an initial combustion chamber enclosing and protecting said electrodes from access of oil, said choke member having a single central opening therein and

said central electrode having an extension of reduced diameter extending through the single opening in said choke member, and a 20 protecting cylindrical sleeve surrounding said choke member and extending substantially below the same, and forming a second chamber, completely open at the bottom but serving to prevent lateral access of oil 25 to the initial combustion chamber, said sleeve having supplemental side electrodes cooperating with the reduced portion of the central electrode, whereby a spark is produced directly in the main combustion chamber of an internal combustion engine. 30

In testimony whereof I affix my signature.

JOHN D. MOORE.
